G. S. G. SPENCE.

Hot Air Furnace.

No. 12,448.

Patented Feb. 27, 1855.

Fig. 1.

Fig. 2.

UNITED STATES PATENT OFFICE.

GEORGE S. G. SPENCE, OF BOSTON, MASSACHUSETTS.

HOT-AIR FURNACE.

Specification of Letters Patent No. 12,448, dated February 27, 1855.

To all whom it may concern:

Be it known that I, GEORGE S. G. SPENCE, of Boston, in the county of Suffolk and State of Massachusetts, have invented a new and useful Improvement in Hot-Air Furnaces; and I do hereby declare that the same is fully described and represented in the following specification and the accompanying drawings, figures, letters and references 10 thereof.

Of the said drawings, Figure 1, represents a central and vertical section of my improved hot air furnace. Fig. 2, is an external elevation of the radiator and fire place or fuel chamber.

In Fig. 1, A denotes the ash pit, B, the fire pot, and D, the fireplace, space, or chamber directly over the firepot and for the reception of flame and the volatile products 20 of combustion that arise from the fuel.

E, is the mouth or charging tube of the fireplace, F being the door thereof.

Out of the top of the chamber D, a series 25 of vertical pipes G, G, G, arranged in a circle are made to lead and to carry the volatile products of combustion directly into a chamber or cylindrical box H, arranged over the fire place D, as seen in the drawings. Out of the top of the chamber H, a 30 discharging pipe I is led for the purpose of conveying smoke from said chamber H, into the atmosphere or into a chimney or discharge pipe. The said pipe I, is provided with a damper K, whose rod L is made to 35 extend through the front casing M, of the cold air chamber N, N, of the furnace. From the middle of the bottom of the radiating chamber H, a pipe or flue, O, is made to lead out of, and down and through the 40 fire chamber or fireplace and over the fire pot B, and out of the fire chamber and into the pipe I, above the damper as seen in Fig. 1. This pipe, O, is provided with a partition, Q, extending across it just above the 45 fire place or flame chamber, D, and such partition has made through it a perforation or orifice R of a size just or about sufficient to keep up the draft and carry off the noncombustible properties of the smoke 50 or volatile products of combustion. This orifice may have a pipe S, extended from it and back into the pipe O, as seen in the drawings, such pipe being

open at its rear end so as to conduct the smoke to the orifice. The flue pipe, O, 55 around or below the pipe, S, and within the chamber, D, and over the fire place, is perforated with one or a series of holes as seen at T, T, the same being for the purpose of discharging into the flame chamber, D, the 60 combustible volatile products or gases that may descend the pipe, O, the discharge of which is greatly facilitated by the pipe, S, as in passing around the same, such pipe operates to prevent them from escaping 65 through the orifice B. By discharging these combustible products into the fire place or flame chamber, they are inflamed and thereby much heat that would otherwise be lost by suffering them to flow directly into the 70 pipe, I, will be saved. By opening the damper, K, the direct passage of the volatile products of combustion into the pipe is secured, while their passage down the pipe, O, will be prevented thereby.

75

My improved furnace in other respects may be said to be essentially like many others in common use.

By carrying a discharge flue, O, through the fire chamber, D, in the manner above 80 stated, I am not only enabled to attain advantages as above specified, but to secure another, viz, that of improving the draft, and particularly directly after a fire is first made in the fire-place, a time when owing to 85 the cool state of the radiator and its discharge flues a downward draft is most likely to take place, and in consequence thereof, more or less smoke is generally thrown out into the room, through the mouth of the 90 fire-place.

I claim as my invention—

1. The carrying the smoke discharge flue of the fire chamber back through the fire chamber substantially as specified whereby 95 the draft of a long flue is promoted.

2. I also claim, carrying the smoke discharge flue of the fire chamber or radiator back through the fire chamber in combination with not only providing it with one or more orifices for the discharge of the combustible properties or gases of the smoke into the fire-place, but with diminished opening or passage sufficient only to carry off the non-combustible volatile portions of 105 the smoke.

3. I also claim combining with the discharge pipe, O, and the orifice, R, the pipe to extend back into the discharge pipe, O, and with respect to the openings, T, T, as specified the same being to facilitate the passage of the combustible gases into the fire-place.

In testimony whereof I have hereunto set my signature this twenty fifth day of March A. D. 1854.

GEO. S. G. SPENCE.
